FIREARM

Original Filed April 13, 1937

Fig. 1

UNITED STATES PATENT OFFICE

2,169,084

FIREARM

William L. Swartz, Wethersfield, Conn., assignor
to Colt's Patent Fire Arms Manufacturing
Company, Hartford, Conn., a corporation of
Connecticut

Original application April 13, 1937, Serial No.
136,630. Divided and this application July 26,
1937, Serial No. 155,609

7 Claims. (Cl. 42—70)

One object of this invention is to provide safety means of novel construction for locking the firing pin of a firearm against movement except when the user is properly gripping the arm preparatory 5 to firing.

Another object is to provide a construction of the above character in which there is substantially no danger of the firearm jamming due to breakage of some of the elements of the firing pin 10 10 safety lock mechanism.

A further object is to provide a safety means of the above character which is operated by a movable member on the grip portion of a firearm, which member also serves to lock the trigger mechanism against movement to firing position except when the user is properly gripping the arm preparatory to firing.

From this specification further objects and advantages of the invention will be apparent to 20 those skilled in the art.

This application is a division of my co-pending application Serial No. 136,630, filed April 13, 1937, Patent No. 2,140,946.

In the accompanying drawing I have shown 25 the embodiment which I now deem preferable, but it will be understood that the drawing is intended for illustrative purposes only and is not to be relied upon as limiting or defining the scope of the invention, the claims forming a part of 30 this specification being relied upon for that purpose.

In the drawing:

Fig. 1 is a side elevation view of a firearm embodying the invention, certain parts being broken 35 away to more fully disclose the invention and other parts being further broken away to show other details.

Fig. 2 is a side elevation view of the breech portion of the firearm of Fig. 1 showing the parts 40 in another position.

Fig. 3 is a horizontal sectional view taken on the line 3—3 of Fig. 1.

Fig. 4 is a vertical sectional view taken on the line 4—4 of Fig. 1.

45 In firearms it is common practice to provide a firing pin which may be forcibly moved into contact with the primer of a cartridge to fire the same. I consider it desirable to provide means for locking such a firing pin against movement to firing position except when the arm is being properly gripped by the user preparatory to firing in order to avoid the possibility of the firearm being unintentionally discharged.

For locking the firing pin a member may be 55 provided which is adapted to move to and from a

position in which it prevents movement of the firing pin into contact with the cartridge. The invention relates to such a locking construction and in accordance therewith I preferably mount a movable member on that portion of the arm 5 which must be gripped by the user preparatory to firing and provide an actuator for transmitting movement from this movable grip member to the lock. The actuator may move the lock either into or out of locking relationship with the firing 10 pin, although for reasons which will be apparent hereinafter I now prefer to have the actuator slidably to move the lock out of engagement with the firing pin.

The invention is susceptible of application to 15 most types of firearms having a firing pin but for the purpose of this specification I have illustrated it in connection with an automatic pistol of the type shown in U. S. Patents No. 984,519 and 1,070,582. As shown in the drawing forming a part of this specification, the pistol 20 comprises a frame or receiver 1, a barrel 2, a reciprocable slide or breech bolt 3, a firing pin 4, a grip 5, a trigger 6, and a hammer 7. In the pistol illustrated the grip is adapted to hold a magazine 25 containing a plurality of cartridges which may be successively fed into the chamber of the barrel, fired, and ejected by repeated retraction of the trigger and automatic reciprocation of the bolt, all in a known manner.

The firing pin 4 is slidably mounted in a hole 8 in the bolt and is urged to retracted position by a spring 9 abutting at one end against a shoulder 10 on the firing pin and at the other end against a portion of the bolt. Rearward movement of 35 the firing pin is limited by a stop 11. The firing pin is of such length that when the hammer is in its uncocked position it may rest against the stop 11 without moving the firing pin sufficiently to cause its forward end to project beyond the front 40 face of the bolt 3. It should, however, be understood that the hammer delivers a sudden blow to the rear end of the firing pin when the gun is intentionally discharged and the momentum of the firing pin causes it to be projected beyond 45 the front face of the bolt to fire the cartridge primer.

In accordance with the invention a firing pin lock 12 is provided which is movable into and out of locking engagement with the firing pin and 50 which may be mounted on any part of the firearm and have any desired type of movement. When used on a firearm of the type illustrated I at present prefer to slidably mount the lock in the bolt which may be transversely apertured as 55

at 13 to receive the lock. Although other forms of locking engagement may be used, I have shown the firing pin as being provided with the shoulder 14 in front of which the firing pin safety lock 12 may project to effectively prevent movement of the firing pin beyond the front face of the bolt. While not strictly essential, I prefer to provide means for biasing the lock and such means is found in the spring 15. In the illustrated construction the lock receiving aperture 13 intersects the rear sight groove 16 in the bolt and the rear sight 17, in conjunction with the firing pin, serves to hold the lock and spring in place, although any desired construction for the purpose may be adopted. The spring 15 is inescapably confined in its receiving recess by the lock and the rear sight; therefore, if the spring should break the pieces could not get into the action of the firearm to cause jamming. The shape of the lock is not critical, the same being only dependent upon the other details of construction used, and in the construction shown it is generally L-shaped with the leg of the L projecting downward, the forward lower corner of which is provided with the cam surface 18. The leg is notched as shown at 19 in Fig. 4 so that the extractor 20 may be removed from the bolt without necessitating the removal of the lock 12.

The means for moving the lock may be of different forms depending upon whether the lock is mounted on the bolt or on the frame, and also depending upon whether the lock is biased, either to or from firing pin engaging position, or not. With the construction illustrated I now prefer to slidably mount a firing pin safety lock actuator 21 in a cavity 22 in the frame, it being held therein by a pin 23 which passes through an elongated slot 24 in the actuator. The actuator includes a portion 25 which, when the parts are in the position shown in Fig. 1, projects upward so that the end thereof is substantially flush with the top of the frame but which, when the parts are in the position shown in Fig. 2, projects above the top of the frame to move the lock 12 out of engagement with the firing pin. The bolt 3 has a groove 26 formed therein for receiving the projecting end of the actuator when it is in its raised position. The lock engaging portion of the actuator 21 projects only slightly above the top of the frame. The frame thus supports the actuator closely adjacent its lock engaging end against the reactionary thrust of the lock as the bolt reciprocates. This construction practically eliminates all danger of the actuator breaking.

In accordance with the invention movable means for operating the actuator is provided on some portion of the firearm which must be gripped, it of course being apparent that the type of movable means provided and its form of connection with the actuator will be dependent upon the specific type of safety lock and actuator adopted for effecting the purposes of the invention. The means for operating the actuator may be designated as a grip safety, the term as used herein being intended to include any such means on the grip which is movable upon properly gripping the firearm preparatory to firing. When the construction takes the form illustrated, a grip safety such as shown at 27 is now preferred. The safety 27 is pivotally mounted in the frame by a pin 28 and it includes a downward extending portion 29 which generally conforms with the shape of the grip. This safety is further provided with a portion 30 which extends beneath

the actuator. A spring 31 serves to bias the grip safety to the position shown in Fig. 1.

The grip safety may, if desired, further function to lock the trigger in non-firing position except when the piston is properly gripped preparatory to firing. In the construction illustrated the trigger 6 includes a trigger bar portion 32 which is adapted to actuate a sear to release the hammer from cocked position. The portion 33 of the grip safety is so shaped and positioned that when the grip safety is in the position of Fig. 1, the trigger is blocked against retraction, but when the parts are in the position of Fig. 2 the trigger may be moved to firing position.

The operation of the disclosed embodiment is as follows:

If the firearm is not being properly gripped preparatory to firing, the parts thereof occupy the positions shown in Fig. 1, that is, the firing pin safety lock is engaged with the firing pin to prevent movement of the latter to firing position should such movement tend to take place due to any cause, and the portion 33 of the grip safety is in a position to prevent movement of the trigger to firing position. If the pistol be properly gripped for firing, the grip safety 27 will be swung inward and consequently the portion 30 thereof will be moved upward. This upward movement will slide the actuator 21 upward which in turn will move the firing pin safety lock out of locking engagement with the firing pin, the pin now being free to be moved to firing position. As the portion 33 of the grip safety is moved upward it also frees the trigger 6 for retraction. Assuming that the pistol is loaded and the hammer cocked, the trigger may now be retracted to release the hammer. When the piston has been fired by contact of the firing pin with a cartridge, the bolt will be caused to slide rearward in a known manner. After the bolt has moved rearward to some extent the safety lock 12 will move out of engagement with the actuator 21 and will be biased by the spring into engagement with the firing pin. Further rearward movement of the bolt will serve to extract and eject the empty cartridge and cock the hammer, all in the usual manner. The bolt will then be moved forward to breeched position but in so moving the lock 12 will come into engagement with the actuator 21 and by reason of the cam surface 18 will again be moved out of locking engagement with the firing pin and the pistol may be again fired as before, assuming that during the forward movement of the bolt a cartridge was fed into the chamber.

If the user's grip on the pistol should now be released the parts would be returned to the positions of Fig. 1 due to the combined action of the springs 15 and 31. It should be noted that the spring 15 not only serves to insure proper movement of the safety lock 12 to locking position but also aids the spring 31 in performing its function, therefore if the spring 31 should for any reason fail to move the grip safety to its safety position the spring 15 would tend to cause such move-

ment. It is apparent that when the pistol is in a substantially upright position, it being shown in an upright position in Fig. 1, the firing pin safety lock will tend to be moved by gravity to locked position even though the biasing spring 15 should be broken.

Alternative forms of the invention set forth in this specification will be apparent to those skilled in the art, and I do not mean to limit myself to

any particular embodiment except as defined in the claims.

What I claim is:

5. The combination with a firearm including a frame, a firing pin, and a grip portion, of a firing pin safety lock, rectilinearly slidable means for moving the lock, and a grip safety movable to operate said slidable means.

10. The combination with a firearm including a frame, a bolt, a firing pin slidably mounted in the bolt, and a grip portion, of a firing pin safety lock on the bolt, rectilinearly slidable means mounted on the frame for moving the lock, and a grip safety movable to operate said slidable means.

15. 3. The combination with a firearm including a frame, a reciprocable bolt, a firing pin slidably mounted in the bolt, and a grip portion, of a firing pin safety lock on the bolt, slidable means mounted on the frame and including a portion engageable with said lock for moving the same, said slidable means being mounted in the frame so as to be supported thereby closely adjacent its lock engaging portion against reactionary thrust 20 of the lock during reciprocation of the bolt, and a grip safety movable to operate said slidable mass.

25. 4. The combination with a firearm including a frame, a bolt, a firing pin mounted in the bolt, and a grip portion, of a firing pin safety lock, a spring for biasing the lock to operative position and being inescapably confined within a recess in the firearm, means for moving the lock to inoperative position, and a grip safety movable to operate said means.

35

5. The combination with a firearm including a frame, a bolt, a firing pin mounted in the bolt, and a grip portion, of a spring, a firing pin safety lock normally biased to operative position by said spring, said lock being movable to operative position by gravity when said firearm is in a substantially upright position upon breakage of said spring, and means including a grip safety for moving the lock to inoperative position.

10. The combination with a firearm including a frame, a firing pin, and a grip portion, of a main sear, trigger mechanism movable from and to a non-firing position and engageable with the main sear to release the same, a firing pin safety lock, a firing pin safety lock actuator, and means 15 mounted on the grip portion directly engageable with the trigger mechanism for normally locking the trigger in non-firing position but movable from normal position to permit trigger movement to firing position and to move said actuator to 20 lock releasing position.

15. 7. The combination with a firearm including a frame, a firing pin, and a grip portion, of a main sear, trigger mechanism movable from and to a non-firing position and engageable with the main 25 sear to release the same, a firing pin safety lock, an actuator for moving the firing pin safety lock to inoperative position, and means separate from said actuator mounted on the grip portion directly engageable with the trigger mechanism for 30 normally locking the trigger in non-firing position but movable from normal position to permit trigger movement to firing position and to move said actuator to release said firing pin safety lock.

WILLIAM L. SWARTZ. 35

CERTIFICATE OF CORRECTION.

Patent No. 2,169,084.

August 8, 1939.

WILLIAM L. SWARTZ.

It is hereby certified that error appears in the printed specification of the above numbered patent requiring correction as follows: Page 3, first column, line 27, claim 3, for the word "mass" read means; and that the said Letters Patent should be read with this correction therein that the same may conform to the record of the case in the Patent Office.

Signed and sealed this 19th day of September, A. D. 1939.

Henry Van Arsdale,

Acting Commissioner of Patents.
